CLAIM

The ornamental design for a spot light, as shown and described.

DESCRIPTION

FIG. 1 is a front, top and left-side perspective view of a spot light showing our new design;

FIG. 2 is a front, bottom and left-side perspective view thereof;

FIG. 3 is a front elevational view thereof;

FIG. 4 is rear elevational view thereof;

FIG. 5 is a left-side elevational view thereof;

FIG. 6 is a right-side elevational view thereof;

FIG. 7 is a top plan view thereof; and,

FIG. 8 is bottom plan view thereof.

The broken lines depict portions of the spot light that form no part of the claimed design. The dot-dash boundary lines define the boundary of the claimed design and form no part of the claimed design.
